Attorney, Agent, or Firm—Quarles & Brady

[57] CLAIM

The ornamental design for a lavatory pedestal, as shown and described.

DESCRIPTION

FIG. 1 is a perspective view taken from the top, front and left side of a lavatory pedestal showing my new design;

FIG. 2 a front elevational view thereof;

FIG. 3 is a top plan view thereof;

FIG. 4 is a cross sectional view taken along line 4—4 of FIG. 3;

FIG. 5 is a right side elevational view thereof, the left side being the mirror image of the right side;

FIG. 6 is a cross sectional view taken along line 6—6 of FIG. 2;

FIG. 7 is a cross sectional view taken along line 7—7 of FIG. 2;

FIG. 8 is a rear elevational view thereof; and

FIG. 9 is a perspective view taken from the top, front and left side of a modified form of the lavatory pedestal shown in FIG. 1, the front, and rear be the same as the front shown in FIG. 2.
